Primary Examiner—Lucy Lieberman(74) *Attorney, Agent, or Firm*—Michael J. Sambrook;
Marianne Dressman; Tara M. Rosnell**CLAIM**

The ornamental design for a dispenser head for cosmetics, as shown and described.

DESCRIPTION

FIG. 1 is a front elevational view of a dispenser, embodying my new design;

FIG. 2 is a side elevational view of the dispenser of FIG. 1;
FIG. 3 is a rear perspective view of the dispenser of FIG. 1;
and,

FIG. 4 is a front perspective view of the dispenser of FIG. 1.

The broken lines showing portions of the dispenser in FIGS. 1 through 4 are for illustrative purposes only and form no part of the claimed design.
